REFLECTOR FOR TUBULAR LAMP LIGHTING FIXTURES

Carl X. Meyer, St. Louis County, and Leo G. Stahlhut, Kirkwood, Mo., assignors to Day-Brite Lighting, Inc., St. Louis, Mo., a corporation of Missouri

Application January 17, 1955, Serial No. 34,028

Term of patent 14 years

(Cl. D48—23)

Fig. 1 is a perspective view, as seen from below, of the reflector for tubular lamp lighting fixtures, showing our new design,

Fig. 2 is a perspective view, as seen from the top, of the same,

Fig. 3 is a top plan view of the reflector shown in Fig. 1,

Fig. 4 is a side elevational view of the reflector,

Fig. 5 is an end elevational view of the same, and

Fig. 6 is a vertical cross-sectional view on the line 6—6 in Fig. 3.

We claim:

The ornamental design for a reflector for tubular lamp lighting fixtures, substantially as shown.
